UNITED STATES PATENT OFFICE.

CHARLES G. JOHNSON, OF BRIDGEPORT, CONNECTICUT.

GRINDING, POLISHING, AND BUFFING MACHINE.

Application filed April 15, 1926. Serial No. 102,194.

This invention relates to machines for grinding, polishing or buffing, and particularly to a machine of this type in which the work to be ground or polished is mounted on a movable support which is reciprocated back and forth to move the work across the surface of the wheel during the grinding, polishing, or buffing operation. Considerable difficulty has been experienced in properly grinding or polishing articles which have a surface which varies and is not entirely in a single plane. For instance, in piano construction there is very often a metal bar used which is flattened on one side and this bar may be of such a shape that a portion of this flattened side may be in different parallel planes or in planes inclined to each other. This article is mentioned merely as an example as, of course, this machine is not limited to use on this kind of an article.

It is an object of the invention to provide a grinding, polishing or buffing machine which will evenly grind or polish the flattened side of such articles as above mentioned or similar articles, and which will automatically shift the article as it is passed by the abrasive surface of the grinding or polishing wheel so that the immediate portion of the surface being ground or polished is automatically positioned relative to the surface of the wheel to maintain the desired contour for this surface.

It is also an object of the invention to provide a machine of this character with a floating work support which is reciprocable past the abrasive wheel, and which has means coacting with other means mounted on the bed of the machine for changing the height of the work support or its angular relation to the surface of the wheel during these movements.

It is a further object of the invention to provide means for automatically shifting the abrasive wheel back and forth longitudinally of its axis during the working operation so as to give more uniform wear to the surface of the wheel and to maintain this surface for a longer time in the shape desired.

It is a still further object of the invention to provide an improved automatic control means for reciprocating the work support.

With the foregoing and other objects in

view, I have devised the construction illustrated in the accompanying drawings forming a part of this specification, similar reference characters being employed throughout the various figures to indicate corresponding elements. In these drawings,

Fig. 1 is a side elevation of the machine.

Fig. 2 is a top plan view with the grinding, polishing or abrasive wheel removed and with a portion of the bed broken away to more clearly show the construction.

Fig. 3 is a rear end elevation looking from the right of Fig. 1.

Fig. 4 is a top plan view of the work support showing a piece of work comprising an irregular bar mounted thereon.

Fig. 5 is a longitudinal section thereof substantially on line 5—5 of Fig. 4.

Fig. 6 is an end view of the work support in Figs. 4 and 5 on a somewhat enlarged scale, and

Fig. 7 is a transverse section thereof.

The machine as illustrated comprises a base or bed 10 supported by suitable legs 11 and on which base the various mechanisms are mounted. Mounted on the top of the base is an upright bracket 12 carrying spaced bearings 13 for a shaft 14 carrying the abrasive wheel 15. This wheel may be a grinding wheel, polishing wheel or a buffing wheel as desired, and ordinarily the working surface is the periphery thereof. Between the bearings 13 there is a pulley 16 over which any suitable belt from a pulley not shown, operated from any suitable source of power, will run for driving the shaft and the wheel. The bearings 13 are preferably adjustable vertically for adjusting the shaft and wheel. For this purpose they are mounted in blocks 17 guided in guideways 18 in the bracket, and adjusting screws 19 are connected to these blocks and pass through a cap 20 on the top of the bracket. The shaft 14 is also mounted for longitudinal or axial reciprocation in the bearings 13 to give a back and forth side-wise movement to the work wheel, as indicated in dotted lines in Fig. 1, so that a greater portion of the surface of the wheel will be employed for the working operation and also to keep this working surface in good condition for a greater length of time, especially in grinding work which is relatively narrow and has a tendency to wear a groove in the surface. During the grind-

100

105

110

ing operation the shaft and wheel are continuously given this reciprocatory movement automatically from the driving mechanism.

5 Mounted at one end of the base 10 is a bracket 21 carrying a short shaft with a drive pulley 22 arranged to be driven from any suitable source of power, not shown, by means of a belt. This shaft carries a pinion 23 meshing with a gear 24 carried on a shaft 25. This shaft carries a cylinder 26 provided with a cam groove 27. There is a bracket 28 secured at the outer end of the bracket 12 to which is pivoted at 29 a lever 30, and this lever carries a roller 31 running in the cam groove 27. At its upper end the lever has tapered guideways 32 for a fork 33, this fork being provided with an elongated slot 34 through which extends a bolt 35. With this means the fork may be adjusted up or down to conform to adjustment of the shaft 14 and clamped in adjusted positions by the bolt 35. The sides of the fork extend on opposite sides of the shaft 14, and on this shaft within the fork is secured a collar 36 having an annular groove 37. The fork carries adjustable studs 38 having enlarged heads or rollers 39 running in the groove 37. It will, therefore, be apparent that as the shaft 25 rotates and with it the cam cylinder 26 the lever 30 will be rocked about its pivot, and through the fork 33 and the collar 36 will shift the shaft 14 and the working wheel 15 back and forth in a direction extending longitudinally of this shaft.

Extending transversely of the base or bed under the wheel 15 is a reciprocating table or slide 40. This table has inclined side walls 41 cooperating with similar tapered guides 42 in the base, and in operation this table is reciprocated back and forth under the abrasive wheel. Mounted on this table so as to reciprocate therewith is my improved floating work support. In the form shown on the drawings this support comprises a substantially flat plate or block 43 of the required length to support the work to be operated upon, and it is mounted on upwardly extending bolts or studs 44 on the slide 40. These studs extend through openings in the support but the openings are sufficiently larger than the studs to allow for rocking movements of the plate. The plate is also mounted on springs 45 about the studs 44 beneath the plate so that the plate is normally supported by these springs to hold the work carried thereby against the surface of the wheel, but it may yield downwardly if required. The upward movement of the plate is limited by means of screws 46 in the upper ends of the studs.

In the drawings, and especially in Figs. 4 to 7, I have shown mounted on this work support a piece of work 47 comprising a

bar of an irregular shape such as the bar in the sounding board of a piano over which the wires are stretched. These bars are bent to various shapes and are usually substantially half round in cross section or are flattened at one side 48. They also usually have a number of holes 49 therethrough. This bar is mounted on the support 43 with the flattened side up, as this is the side which is to be ground or polished. These bars very often are not only curved in a horizontal plane, as shown in Fig. 4, but they are also often curved in a vertical plane, as shown in Fig. 5, and in addition may be twisted somewhat, as shown in Figs. 6 and 7. It so may be mounted on the support 43 by suitable pins 50 extending into the openings 49, and the higher parts may rest on V-shaped supports 51.

It will be obvious that if the surface of such an article as this is to be ground or polished uniformly it should be presented to the surface of the work wheel in various positions, that is, at various heights from the bed and also in various angular positions. I secure this effect by providing cams on the support 43 cooperating with rollers carried by the bed of the machine, and in the arrangement illustrated these cams comprise bars 52 mounted on the top 90 of the plate 43 along the opposite side edges thereof, and the top surfaces of these bars are given shapes depending on the shape of the bar 47 to be polished. Thus adjacent the opposite ends of this bar, for instance, where these ends are raised above the plate 43, as shown in Fig. 5, the top of the cam bars will be correspondingly raised and they will be lower in the center while if a portion of the surface of the work is not parallel with the support the cam on one side may be lower than the cam on the other side so as to rock or tip the plate 43, as shown in Fig. 7, to bring the surface of the work parallel with the surface of the work wheel. The cams 52 coact with rollers 53 which are mounted on levers 54 and 55 so arranged that as the table 40 and the work holder 43 are reciprocated back and forth these rollers 53 will run along the 105 tops of the cam bars 52 and will raise or lower the plate 43 or give it a rocking movement, as shown in Figs. 6 and 7, to properly present the flattened side 48 of the bar 47 to the surface of the wheel 15 and with a 120 uniform pressure, so that the surface of this flat side will be uniformly polished or ground, and the liability of grinding off one portion more than another because of the irregular arrangement of this surface will 125 be obviated.

The lever 54 is pivoted at 56 on a bracket 57 mounted on the bracket 12, and at its opposite end has a finger or extension 58 connected by means of a spring 59 with a hook 130

60 carried by the bracket 12. An adjustable stop 61 is mounted in the bracket with its lower end above the lever and acts as a stop to limit the movement of the lever 5 under the action of the spring. The lever 55 is pivoted at 62 in a bracket 63 on the bed 10. Extending upwardly and outwardly from this bracket is an arm 64 carrying a spring 65 connected to the outer end of 10 the lever. The bracket also carries an adjustable stop 66 arranged to engage the top of the lever to limit its movement under the action of the spring. It will be apparent from an inspection of Figs. 1, and 4 to 7 15 that the plate or work support 43 is mounted for substantially universal movement, or that is, what I call a floating work support as it may move up or down or have rocking movements, and the positions both as to 20 height above the table and its angular relation to the abrasive wheel are controlled by the rollers 53 coating with the top surfaces of the cam bars 52. The pressure of the work against the surface of the wheel 25 is controlled by the springs 45, 59 and 65. For best results the rollers 53 should be located substantially on the vertical central line of the wheel 15.

As the table 40 may be of considerable 30 length there may be extensions for the guides 42 beyond the sides of the base 10. For this purpose brackets 67 may be secured to the opposite sides of the bed and have guides similar to the guides 42. The table is reciproated automatically during the grinding or polishing operation. I have shown improved means for giving the table this reciproating movement. Secured to the under side of the table and extending throughout substantially the entire length thereof 40 there is a rack 68 meshing with a gear 69 on a shaft 70 beneath the bed. This shaft has an enlargement 71 on which is a sleeve 72 arranged to turn thereon, and keyed to 45 this sleeve, as shown at 73, is a bevel gear 74. This bevel gear meshes with an idling bevel gear 75 mounted on a shaft 76 and this gear in turn meshes with a bevel gear 77 on the shaft 25, either keyed to this shaft or 50 pinned, as shown at 78. Between the gear and shaft is a sleeve 79 carrying a series of teeth 80 adapted to mesh with teeth 81 in a block 82. The other end of this block has teeth 83 directed in the opposite direction and adapted to mesh with teeth 84 on 55 the sleeve 72. The block 82 is mounted on a sliding shaft 82' having driving engagement with the shaft 70 at all times so that as the block 82 is rotated it will rotate the shaft 70 and the gear 69 carried thereby. The block 82 is mounted so as to be shifted 60 to engage either the teeth 80 on the sleeve 79 or the teeth 84 on the sleeve 72, and as the sleeves 79 and 72 are rotated in opposite 65 directions it will be obvious that the gear

69 will be rotated in opposite directions depending on with which sleeve the block 82 is in engagement. The block is shifted by means of a fork 85 running in a groove 86 in the block. This fork is carried on a block 70 mounted on a shiftable rod 88. This rod is mounted in bearings 89 and carries stop collars 90 arranged to engage the bearings to limit the lateral movements of the rod. The block 87 is connected to a lever 91 pivoted to the base at 92. The end of the lever has a sliding engagement with a circular element 91' carried by the block 87. This lever is connected by a link 93 with a bell crank 94 pivoted to the base at 95. The other 75 arm of this bell crank is connected by link 96 to a shiftable bar 97 which carries a rack 98. This bar is mounted to slide in suitable bearings 99, and stop collars 100 limit the movements of this bar. The rack 98 meshes with a gear 101 on a shaft 102 mounted in suitable bearings on the under side of the base. A hand lever 103 is mounted on the shaft by means of which the same may be turned to rotate the gear 101. This shaft 102 also carries an arm 104 projecting upwardly through a slot 105 in the base 10 in the path of movement of dogs or lugs 106 carried by the table 40. There is only 80 one of these dogs shown on the drawing, but it will be understood there will be a similar dog adjacent the other end of the table to engage the opposite side of the arm 104 and shift the clutch mechanism to reverse the movement of the table. This means for reciproating the table is especially adapted 85 for this kind of a machine where a relatively long table is used. It will be obvious that the gear and rack drive 68-69 may be used with practically any length of table desired 90 as its operation is not dependent on the length of the table and tables of different lengths may be used on this machine without changing the reciproating mechanism 95 and the reversing mechanism therefor. 100

It is thought the operation of this mechanism for shifting the table will be obvious. If the table is moving upwardly, as viewed in Fig. 2, the dog 106 will engage the arm 104 and swing it upwardly to shift the bar 115 97 downwardly. This movement acting through the bell crank 94 and lever 91 will shift the block 82 from engagement with the teeth 80 on sleeve 79 into engagement with the teeth 84 on sleeve 72 and will reverse the movement of the table. Of course, when the table reaches the end of this reverse movement the other dog will engage the arm 104 and swing the clutch mechanism back into engagement with the sleeve 79 and 120 so on. The dogs or tripping block 106 are adjustably mounted on the table so that they may be shifted to vary the point at which the reversing mechanism will be tripped. 125

It will be apparent from the foregoing de- 130

scription that with my improved work support the surfaces of an irregular piece of work may be properly and uniformly presented to the surface of the wheel to secure the desired uniform operation thereon throughout the entire surface to be worked. The lateral reciprocatory movement of the wheel will utilize substantially the entire working surface thereof and prevent wearing of grooves in the surface, so that it will be maintained in grinding or polishing condition for a longer time without requiring to be dressed, and the reversing movement for the table will give a reliable and automatic reciprocation of this table to move the work back and forth under the wheels, and this movement will cooperate with the cams carried by the work support to properly present the work to the surface of the wheel. The hand lever 103 permits reversing of the table at any time, while placing of the block 82 in the intermediate position will stop the feeding movements of the table. It will, of course, be understood that the construction and arrangement of the work support, the cams 52 and the elements associated therewith may be varied considerably without departing from my invention. For example, the springs, the cams and the levers 54 and 55 may be reversed and secure the same operation. This would bring the cams on the under side of the support instead of the top. It is also to be understood that the term grinding wheel or abrasive wheel used in the specification and claims is used in the broad sense as indicating a grinding wheel, a polishing wheel or a buffing wheel.

Having thus set forth the nature of my invention, what I claim is:

1. In a grinding and polishing machine, an abrasive wheel, a work support mounted for substantially universal movement including lateral and longitudinal rocking movements, means for shifting the support to present the work to the wheel, and cam means for determining the height and angular position of the support as it passes by the wheel.

2. In a grinding and polishing machine, a peripheral grinding wheel, a work support mounted for longitudinal movement past the wheel and also for longitudinal and lateral rocking movements, cam elements on said support, and means cooperating with said cam elements to determine the angular position of the support as it passes by the wheel.

3. In a grinding and polishing machine, a grinding wheel, a work support mounted for up and down and lateral rocking movements, means for passing the support by said wheel, cams carried by the support, and yieldably mounted means on opposite sides of the support engaging said cams and cooperating

therewith during said movement to position 65 said support.

4. In a grinding and polishing machine, a grinding wheel, a work support mounted for up and down and rocking movements, means for passing the support by said wheel, cams 70 carried by the support on opposite sides of the wheel, pivoted levers on opposite sides of the support, rollers carried by the levers engaging said cams, and springs tending to hold the rollers against the cams. 75

5. In a grinding and polishing machine, a grinding wheel, a table, a work support mounted on the table for rocking movements, means for reciprocating said table to pass the support by the wheel, upright studs on 80 the table, springs on the studs for carrying the work support, cams carried by the support on opposite sides of the wheel, and yieldingly mounted rollers engaging said cams to determine the rocking movements of 85 the support.

6. In a grinding and polishing machine, a peripheral grinding wheel, a floating work support mounted for up and down and lateral and longitudinal rocking movements, 90 means for passing the support by the periphery of the wheel in substantially the plane of the wheel, a pair of cams carried by the support and extending longitudinally of the direction of movement of the support, 95 and means cooperating with the cams to determine the angular position of the support with respect to the wheel.

7. In a grinding and polishing machine, a frame, an upright rotatable abrasive wheel, 100 a table mounted on the frame below the wheel for longitudinal reciprocating movements in the plane of the wheel, a work support mounted on the table and extending longitudinally thereof, said support being 105 mounted for up and down movements and lateral and longitudinal rocking movements, means on the support for holding the work to be operated upon, cams mounted on the support on opposite sides of the work and extending longitudinally of the support, and separate means mounted on the frame cooperating with said cams as the support reciprocates to determine the angular positions of the support. 110 115

8. In a grinding and polishing machine, a frame, an upright rotatable abrasive wheel, a table mounted on the frame below the wheel for longitudinal reciprocating movements in the plane of the wheel, a work support mounted on the table for up and down and lateral rocking movements, means on the support for securing the work to be operated upon, cams mounted on the support on opposite sides of the work and extending longitudinally of the support, levers pivotally mounted on the frame on opposite sides of the support, rollers carried by said 120 125

levers and engaging said cams to cooperate therewith to determine the angular positions of the support, and springs connected to the levers and acting to hold the rollers against 5 the cams.

9. In a grinding and polishing machine, a frame, an upright rotatable abrasive wheel, a table mounted on the frame below the wheel for longitudinal reciprocating movements in the plane of the wheel, upright guiding studs mounted on the table, a work support loosely mounted on the studs for up

and down and lateral rocking movements, springs between the table and the support to sustain the support, means on the support 15 for retaining the work to be operated upon, a pair of cams mounted on the support and arranged to rock the support in opposite directions, and rollers mounted on the frame to engage said cams as the support is reciprocated.

In testimony whereof I affix my signature.

CHARLES G. JOHNSON.
